UNITED STATES PATENT OFFICE.

RICHARD HANSON CABENA, OF CROYDON, ENGLAND.

HEATER OR SUPERHEATER FOR STEAM, AIR, OR GASES.

1,332,943.

Specification of Letters Patent.

Patented Mar. 9, 1920.

Application filed June 8, 1915. Serial No. 32,838.

To all whom it may concern:

Be it known that I, RICHARD HANSON CABENA, a subject of the King of Great Britain, residing at 120 Sydenham road, in the county borough of Croydon and county of Surrey, England, have invented Improved Heaters or Superheaters for Steam, Air, or Gases, of which the following is a specification.

10 My invention relates to steam, air or gas heaters or superheaters and is intended more particularly for application to steam generators, and especially for a superheater for use in connection with vertical steam 15 boilers.

In steam superheaters it is common to employ what are known as field tubes,—consisting of an inner open ended, or through, tube and an enveloping tube closed at the outer, or free, end,—dependent from a two-chamber header, or field tubes arranged horizontally.

According to the present invention, I employ inverted field tubes standing up from 25 a two-chamber header and arrange in combination therewith one or more deflectors or dampers which stand in or are arranged to be brought into a position obliquely to the path of the flue gases and direct the hot flue 30 gases from the uptake or flue over around and among the said tubes. These deflectors may be adjustable as to position and may also be pivoted, balanced and geared together, if desired. One or more further deflectors may be employed to direct the hot 35 gases from the upper part of said tubes to the exterior of the device, and these upper deflectors may also be geared to the lower deflectors so as to move simultaneously 40 therewith in order that both upper and lower deflectors, when required, may be folded parallel with the tubes and shut off the flue gases altogether from the superheater.

45 The field tubes may be fitted at intervals in their height with grids to keep them in proper position. The space between the outer and inner tubes is very small so as to insure a high velocity of the air, gas or 50 steam passing down between the outer and the inner tubes. The steam, air or gas enters the lower chamber of the header and is there distributed to and passes up through the inner tubes of the field couples, and returns to the upper or collecting chamber of 55 the header, through the annular space be-

tween the inner and outer tubes. In its passage it becomes heated or superheated by contact with, and radiation from, the hot walls of the tubes. From the collecting 60 chamber it is drawn off at any suitable point for transmission to the steam engine, or machine, or apparatus wherein it may be required to be used.

The objects of the improvements are, first, 65 to regulate the amount of heat or superheat according to requirements; second, to permit of easy cleaning of the heating surfaces; third, to effect a high degree of heat abstraction per unit of surface, and a high 70 degree of superheat; fourth, in the case of vapors such as wet steam, to effect a natural drainage, to reduce the carrying over of liquid particles, and deposition of solid matters that may be contained therein.

75 As applied to a vertical boiler (see Figs. 1, 2, 3) the superheater is arranged beside the chimney or uptake and above the crown of the boiler in such a way as to provide a lateral chamber or chambers through which 80 the flue gases are or can be directed when the superheater is required to operate.

The flue gases meet a deflector adapted to stand obliquely to the path of the gases and to direct them on to the lower part of the 85 nest of tubes of the heater or superheater. The gases then rise around these tubes and pass away therefrom at the top of the device. A second deflector may if desired be arranged above the first to direct the escape 90 of the hot gases. These deflectors may be geared together so as to be balanced and move simultaneously and to shut off the superheater when required.

In the accompanying drawings I have 95 shown a superheater adapted to work with a vertical boiler.

Figure 1. is a sectional elevation of the superheater, on the line A—B in Fig. 3.

Fig. 2. is an elevation viewed in the direction A to B in Fig. 3, and in part section on C—D in Fig. 1. with the plate 1. removed.

Fig. 3. is a plan of Fig. 1. with the chimney plate 2, and cleaning door 3, removed.

Fig. 4. is a sectional elevation showing a method of forming and fixing the inner and outer tubes of the field couples so as to form stays for the flat surfaces of large headers.

In these drawings similar numerals refer 110 to similar parts.

The superheater device is constructed with

straight tubes 4 closed at one end and screw-threaded or otherwise secured at the other end in a tube-plate 5 with inner open-ended tubes 6 fitted therein, said tubes being screw-threaded or otherwise secured in a second tube-plate 7; the space between the two tube-plates 5, 7, forms the collecting space or chamber for superheated steam, the supply being taken from the farther side of the 5 second tube-plate 7. The nest of tubes is preferably mounted so as to stand vertically upward from the top surface of a double box-chamber or header which provides the collecting spaces, the upper (5) and the middle (7) walls of the box-chamber receiving the open ends of the respective sets of tubes 4, 6. The tubes 4 and 6 are (at top) preferably of square or similar section at their tops so as to take a key or spanner for the 10 insertion or removal of the tubes. The internal tubes are with advantage reduced in cross sectional area for a short distance at their upper ends to cause a high velocity of steam at exit. A cleaning and inspection 15 cover or door is shown at 3.

On the drawings, see Fig. 1, pivoted flaps or deflector doors 8, 9, are provided to regulate the path of the hot gases, the two flaps being connected together if desired for example by means of intermeshing pinions 10, 11, upon their spindles, preferably in such a manner that they balance each other. By means of these two deflectors the superheater can be shut off from the flue gases as occasion 20 may require for cleaning the tubes or for repairs, while allowing ordinary use of the boiler. These deflectors also allow the control of the quantity of the gases passing to the tubes. The upper reflector also serves 25 to prevent the formation of eddies in the upper part of the superheater and assists in directing the flue gases outwardly from the apparatus. The pinions 10, 11, are shown controlled by a single operating lever 12, balanced and adapted to engage a notched rack 13 mounted on the exterior of the shell 30 of the superheater device; see Fig. 3.

The other sides of the superheater chamber may be inclosed by means of plates fitted 35 together in a detachable manner so as readily to permit access for cleaning and inspection. Doors may be provided for inspection or cleaning purposes.

The box-chamber which forms the header 40 of the superheater and comprises the tube-plates 5, 7, is preferably mounted on a rectangular flange 14, extending to one side from a base plate 15, which fits upon the upper end of the uptake or the uptake-liner 45 of the boiler. This box chamber comprises a lower inlet chamber 17^a having an inlet 17 and an upper outlet chamber 16^a having an outlet 16.

The path of the hot gases from the uptake 50 of the boiler is deflected by the flap 9, which

is shown (in Fig. 1) standing obliquely to their path, on to the lower part of the exterior of the tubes 4. The gases thence rise around these tubes to the top of the superheater device and then pass across the latter 70 and escape through the outlet 20. Where the second flap or deflector 8 is employed it assists in directing the gases out through 20.

It will be evident that two or more superheater sections or nests of tubes may be provided around the boiler flue, either on the same or on opposite sides, the headers and tubes being coupled in series or in parallel. One or more separate deflectors or pairs of deflectors may be provided for the several 75 sections. In other words, the superheater shown in Fig. 1 may be duplicated on the other side of the boiler uptake and flaps or deflectors be employed to direct and spread the hot flue gases toward each set of tubes, 80 the flaps being geared together and movable simultaneously if desired.

The upper deflector 8 may be dispensed with if desired, or a single pivoted deflector may be arranged to swing either up or down 90 or to take up a horizontal position, when the superheater is in use.

The superheater tubes may be cleaned by means of steam jets, a perforated tube being placed inside the casing for example. 95 Scrapers may be provided to clean the tubes, of ordinary construction.

Since the tubes 4 are supported only at their lower ends I may if desired fit a grid or grids (not shown) over or around the 100 tubes 4, at or toward their upper portions, so as to keep the tubes parallel with one another. Other grids may also be provided as baffle plates lower down the tubes 4. These intermediate grids would not extend around all the tubes but would cause the hot 105 flue gases to follow a zig-zag or sinuous path in their upward movement around and along the tubes 4. The grids may be rigidly secured to the casing of the apparatus.

The tubes 4, 6, are secured in place by screwing into tapped holes in their respective tube-plates. Calking rings 21, Fig. 4, may be provided around the tubes 4, the latter preferably having a slight taper to 115 the threaded portion, and the counterbore in the tube-plate 5 being rough-machined to receive the calking ring. These rings should be of metal having the same expansion approximately under heat, as the metals of the 120 tube and tube-plate. They may be solid as when cut from tube, or may be formed from strip or rod metal.

In the method of securing the tubes shown in Fig. 4, the three walls of the header 5, 7, 125 22 are tapped, the outer tube 4 being screwed into two of the walls 5 and 7, and preferably with a calking ring 21 at the outer surface; the internal tube has an enlarged end 23 which screws into the bore of the external 130

tube 4, and into the third wall 22 of the header. Holes 24, 25, are drilled transversely through the two tubes 4, 6, to allow passage of steam, and a screw plug 26 closes the end of the internal tube. The whole arrangement resembles a boiler stay-tube and presents many advantages in practice when used on large headers with otherwise unsupported flat surfaces.

10 The tubes are preferably arranged in the vertical position described, so as to facilitate drainage. By the inverted arrangement of field tubes vertically or approximately so, drainage by gravitation is attained. By 15 providing only a small annular space (for instance $\frac{3}{16}$ " or $\frac{1}{16}$ ") between the tubes a high velocity of steam is obtained whereby a higher rate of absorption of heat is gained and a higher degree of superheat. The high 20 steam velocity also clears away or prevents accumulation of deposit from moist steam that would otherwise take place to the detriment of heat abstraction and causing blocking of the passages. The increase in rate of 25 heat absorption enables shorter tubes to be used and less extent of tube surface. The smaller outlet ends of the inner tubes discharge the steam at a high velocity near the closed ends of the outer tubes and in this 30 manner clear away or prevent any deposits which might otherwise occur.

In some cases the deflector may be a fixture of refractory material but I prefer to employ a deflector which is adjustable as to 35 position. When the deflectors are of metal they may have a saving-plate attached of the usual type and any suitable form easily renewable.

Sliding dampers or deflectors passing 40 through a slot or opening in the wall of the casing adapted to direct the flue gases into the superheater may be employed.

When applied to other types of boilers

than the vertical type the casing or shell, or portions thereof, may be formed by the 45 brickwork of the boiler setting, or by the casings of the boilers or flues where these are of metal.

The invention may also be applied to the heating of gases or of air *e. g.* for use with 50 oil burners or supplying hot air to furnaces in which case the separator device would be dispensed with. The air would be passed through the apparatus on its way from the air blower to the burner in a like manner 55 to the passage of steam.

The part of the superheater comprising the tubes and header may be made detachable from the deflector-provided portion if desired.

Having now particularly described and ascertained the nature of my said invention, and in what manner the same is to be performed, I declare that what I claim is:—

In a system of the class described a heat 65 conducting flue, a superheater embodying a casing, a plurality of vertical inverted field-type outer and inner tubes therein, uniformly self-balancing externally geared deflector-doors arranged in pairs to open or 70 close communication between the flue and the casing and having an oscillating movement, said doors being so constructed and arranged as to direct the hot flue gases from the flue toward, on to, and among the said 75 outer field-type tubes substantially at their bottoms, then upwardly and among these tubes, and finally returning the spent flue gases to the aforesaid flue, thereby providing a contraflow process of the heating gases, 80 the steam or gases being heated or superheated in the outer or incasing tubes, and soot-cleaning doors adapted to maintain the efficiency of said incasing tubes, fitted directly over their top ends.

RICHARD HANSON CABENA.
